UNITED STATES PATENT OFFICE.

GEORGE KRELL, OF KANSAS CITY, MISSOURI.

WELL-CASING ELEVATOR.

Application filed December 4, 1922. Serial No. 604,758.

To all whom it may concern:

Be it known that I, GEORGE KRELL, a citizen of the United States, residing at Kansas City, in the county of Jackson and State 5 of Missouri, have invented certain new and useful Improvements in Well-Casing Elevators; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 This invention is a continuation in part of an application filed by me on or about July 22, 1922, Serial No. 576,699 and it relates to oil well casing elevators.

20 The primary object of the invention is to provide an elevator which may be conveniently operated to cause jaws to engage and disengage the pipe with the gripping engagement of sufficient firmness to prevent slipping of the pipe or casing.

25 An important feature of the invention is that the elevator jaws engage the surface of the pipe below the collar in contra-distinction to those types of elevators which suspend the pipe from the collar so that the 30 collar takes the load. Where the entire pipe or casing is suspended from the collar or one section, the weight often is sufficient to tear off the collar because the collar cannot sustain the load. Existing types of elevators now in general use throughout the 35 oil fields have this defect. The objection to suspending the load from the collar will be appreciated when it is considered that a string of casing sometimes weighs from 40 fifty to sixty tons not considering friction and where the elevator is so constructed that the entire load is suspended from the collar resting on the elevator, the collar frequently collapses and it is the elimination of this 45 important defect which is of prime importance.

In actual field operations there are certain mechanical difficulties encountered which, if not provided for, will render any 50 elevator unsuccessful; for example, the pull on the hoisting cable is not always in line with the axis of the casing, in fact it is more frequently off to one side, so, unless provision is made for equally holding the 55 pipe or casing irrespective of the line of draft or pulling, there will be a tendency

to put a kink in the pipe; that is, to slightly disrupt its wall and it is an invariable rule in the oil fields that a casing section or pipe which is not perfect is immediately discarded.

60 Another operating condition which must be taken into account is that the casing is pulled by the cable suspended from the top of the derrick and while the oil rigging is 65 in place. The end of the walking beam is very close to the vertical axial line of the casing or hole although a considerable distance above it and, indeed, when the hole is being drilled, the end of the walking 70 beam straddles the hole so that the notch for the temper screw will be practically in line with the center of the hole. When the casing is to be pulled, the walking beam is tilted so that its free end is swung in an 75 upward direction to throw it as far away from the center of the hole as possible but the clearances are such that only a slight swinging movement is permitted and since the elevator passes the end of the walking 80 beam either in lowering the casing or pulling it, it is apparent that the elevator must be compact, taking up little room and yet have sufficient strength to support the pipe because the entire weight of the casing or 85 pipe is hung on the elevator when it is being lowered into the well or when it is being raised. The spider which holds the pipe between the elevating or lowering operation can be larger because it has a fixed 90 position but this is not true of the elevator on account of its up and down movement in actual practice.

95 Further, a successful elevator must be capable of taking different sizes of casing. If the elevator is not capable of gripping with equal facility different diameters of casing, it would be necessary to use a different elevator on each size of casing and as is well known, all oil wells require different sized casings.

100 My invention contemplates the elimination of the afore-mentioned difficulties and particularly in that it is strong enough to support the heaviest known weights, is compact, is adapted to hold different diameters of casings, and a by no means unimportant feature of my invention is the provision of means for opening the jaws of the elevator so that the elevator can be slipped over the 110 collar on the end of the casing and in order to assist in the application of the elevator

2
to the casing and the removal therefrom I provide means for holding the co-operating jaws in position to move into casing-gripping position when the opening mechanism 5 is released. The jaws are self-seating in that they find their own gripping positions by their own weights and after they have engaged the pipe, the supporting links or the cable may be deviated from a vertical 10 line in any direction without affecting the uniform gripping action of the jaws.

The novel features of this invention will be understood by reference to the following description in connection with the accompanying drawings, in which

15 Fig. 1 is a perspective view of the upper portion of a string of casing showing the elevator applied, the string being secured in a spider, part of the derrick and part of the 20 walking beam as well as the calf wheel being shown in perspective.

Fig. 2 is a detail perspective view of an elevator constructed in accordance with my invention.

25 Fig. 3 is a sectional view on the line 3—3 of Fig. 7.

Fig. 4 is a sectional view on the line 4—4 of Fig. 6.

30 Fig. 5 is a sectional view on the line 5—5 of Fig. 4.

Fig. 6 is a side elevational view of the elevator in casing-clamping position.

Fig. 7 is a like view with the jaws out of casing-engaging position.

35 Fig. 8 is a vertical, sectional view showing the positions of the jaws when the parts are in the position shown in Fig. 6, and

Fig. 9 is a like view of the jaws when the 40 parts are in the position shown in Fig. 7.

Referring now to the drawings by numerals of reference:

1 designates the derrick which may be of usual construction. The top of the derrick may support a tackle consisting of the cable 2, the block 3 and the hook 4, the cable being raised and lowered from the calf wheel 5. The walking beam 6 is provided with the usual bifurcated end 7 and notches 8 to receive the temper screw head, and the walking beam may rest upon the end of the headache post 9 whenever expedient. The floor 10 of the derrick may support a spider 11, from which the casing 50 55 may be hung. The casing section 12 may support the string of casing sections in the well, the load being carried by the spider 11 unless the string is suspended from the elevator through the casing section 13. This 60 much of the apparatus described is old and per se constitutes no part of my invention.

My invention consists rather in the elevator adapted to co-operate with these known elements in such a manner as to require no reorganization of the known ele-

ments and which can operate without interfering with them.

The elevator is shown as comprising a frame consisting of two side bars 14 and 15, the ends of which are connected by shafts 16 and 17. The shaft 16 is mounted in bearings 18 and 19 on the side bars 14 and 15, and the shaft 17 is mounted in similar bearings 18' and 19' on the ends of the side bars 14 and 15 distant from the bearings 18 and 19. Therefore, the bars 14 and 15 and the shafts 16 and 17 provide a substantially rectangular frame. The frame is suspended by inverted, U-shaped bails 20 and 20', which have bearings 21 and 21' through which the shafts 16 and 17 project so that the frame can be suspended from the bails 20 and 20'. The bails are adapted to be hung on the hook 4 or a similar support.

Between the bearings on the bails and the bearings on the side bars are toggle levers. The toggle levers 22 and 23 have trunnion bearings 24 and 25 to receive the trunnions 26 and 27 of the jaw member 28. Toggle

levers 29 and 30 are carried by the shaft 17 and have trunnion bearings 31 and 32 in which are mounted the trunnions 33 and 34 of the jaw member 28'. The two jaw members have half round or concave seats 35 and 36, in which are removable slips or toothed lining members 37 and 38, adapted to be secured in the jaw members by removable set screws 39 and 40 (see Fig. 9). The side bars, the toggle levers and the jaws may be of rough casting but the insert or lining members 37 and 38 will preferably be of machined steel because it is desired to make the lining of a better grade of steel than the rough casting so that it will bite into the pipe or casing to be engaged.

When the lining members have become worn they may be readily removed and new ones substituted without the necessity of purchasing entirely new elevators. The removal can be effected by loosening the screws 39 and 40.

The jaw members will have a tendency to swing one toward the other because they are pivoted above the point at which the toggle levers or links 22, 23, 29 and 30 are pivoted to the shafts 16 and 17, and they may have a tendency to tilt one with respect to the other but in order to prevent this, I provide lugs 41 and 42 on the jaw member 28 and similar lugs 43 and 44 on the jaw member 28'. The lugs 41 and 43 have aligning openings 45 and 46 and the lugs 42 and 44 have similar openings 47 and 48. All of the openings are larger than the respective stabilizing or position-retaining rods 49 and 50, which pass through the openings 45 and 46 and 47 and 48 respectively. The rods 49 and 50 will prevent the upper edges of the jaws from tilting one toward the other but the

rods will not fit in the openings so tight as to prevent the jaws from becoming self-seating as it is very important in the construction of an elevator that both jaws find their own seats on the periphery of the casing.

If the rods maintained the two jaws in strict parallelism, this would be a disadvantage because there would not then be uniform application of gripping pressure at diametrically opposite points on the casing when the draft of the cable was to one side of the axis of the casing, as it often is in practice. The rods 49 and 50 are not to maintain parallelism of the jaws but merely to hold them in position so that the jaws will be retained in vertical positions, the play between the rods 49 and 50 and the lugs permitting the jaws to automatically seat on the casing which they engage.

In practice I prefer to place spacing collars 51 and 52 on the rods 49 and 50 between the jaws, as will be clearly seen in Fig. 4. These spacing collars will prevent the jaws from coming so close together that the diameters of the openings between them will be less than the diameter of the casing to be engaged.

An elevator for oil well casing is essentially a heavy structure because it has to support a heavy weight and it is, therefore, difficult to pry the jaws apart by hand when it is desired to release the casing. I have, therefore, provided a novel form of jaw spreader and this is best shown in Figs. 6 and 7. The jaw spreader is shown as consisting of a hand lever 53, which is pivoted on one of the bearings 18 of the side bar 14 (see Fig. 5). The hand lever 53 carries a detent consisting of the link 54, connected to the swinging hand grip T-shaped lever 55 and having at one end a bolt or pawl 56 which is adapted to engage in the notch 57 in one of the bearings 18 of the side bar 14. The hand lever 53 carries an angular extension or arm 58, having a slot 59 therein and a cam edge 60 on which may ride a connecting pin 61 for two links 62 and 63 which are, in turn, connected to the jaws. Therefore, when the lever 53 is swung in the position shown in Fig. 6, the arm 58 will be swung downward, drawing the connected ends of the links 62 and 63 downward and allowing the jaws to come together. This will not be necessary ordinarily because the weight of the jaws themselves will cause them to come together.

The difficulty will be in opening the jaws. Then it is necessary to swing the lever 53 in a position as shown in Fig. 7 with the arm 58 swung upwardly to cause the toggle links 62 and 63 to spread and thereby move the jaws apart, as shown in Figs. 7 and 9. The jaws will be held in the spread position by the detent or bolt 56, engaging the notch 57 in the end of the side bar 14.

The toggle links or levers which carry the jaws are free to move about the axis of the shafts 16 and 17 so that they can readily drop into casing-engaging position, irrespective of the pull on the bails 20 and 20'. In other words the toggle levers 22, 23, 29 and 30 are free to swing on the shafts 16 and 17, consequently, the jaws 28 and 28' loosely trunnioned in the links or levers will be self-seating. Since the bails are also loose on the shafts 16 and 17, it is obvious that they can turn about the shafts when the pull of the cable 2 is to one side or the other without disturbing the jaws and since it is very important that the jaws maintain uniform contact throughout their areas with the casing, the freedom of movement of one set of elements independently of any other set will be clearly appreciated. Attention is especially directed to the fact that the construction shown permits of a compact organization which can be built of sufficient strength to support extremely heavy strings of casing and yet be constructed within the limits made necessary by the peculiar construction of the drilling apparatus with which the elevator must operate.

When the elevator has gripped the pipe and the cable is raised by winding it on the bull wheel 5, the pipe or casing string 95 would not be raised unless it was released from the spider. The releasing of the slips 64 in the spider 11 is well known practice and will be well understood by those skilled in the art.

When the slips 64 are released, the casing can be pulled by the elevator. If the casing is being lowered, the top section 12 in the well will be held in the spider by the slip 64 but if the casing is being pulled, 105 the section second from the top, as indicated at 12, will be secured in the spider by the slips 64. Then the elevator will be released and the top section 13 unscrewed from the collar of the section 12. The elevator will then be lowered until it grips the section 12 and raises it to the position shown in Fig. 1. The section under 12 will then be held by the slips in the spider 11 and the top section taken off. This will 110 continue until the casing has been pulled.

In lowering the string into the well, the slips 64 will be taken out while the section 13 is held by the elevator; then the entire string can be lowered into the well 120 until the section 13 assumes the position shown in full lines with respect to the section 12 in Fig. 1. Then the slips will be put in place to hold the section 13 and another section will be screwed into the top 125 of 13, the elevator will be attached to the top of it in the same manner as is shown attached to the top of the section 13, and then the string will be lowered further into the well. This will continue until the de- 130

sired amount of casing is lowered into the well.

It will be apparent from the foregoing that the device is compact, simple to operate, that the jaws will be self-seating in operation but that they may be readily spread apart and held in position to take different sizes of casing, and that since the jaws will be held in a vertical position and not in perfect parallelism, they will readily slip over the collars of the casing either for lowering or pulling the casing and even if the pull is to one side or the other, the jaws will still grip the casing uniformly.

What I claim and desire to secure by Letters-Patent is:

1. A casing elevator comprising a frame consisting of side bars and transverse shafts connecting them, bails loosely mounted on the shafts for supporting the frame, rocking levers carried by the shafts and operable to open and close independently of the movement of the bails, and elevator-casing-engaging jaw members carried by the rocking levers.

2. A casing elevator comprising a frame consisting of side bars and transverse shafts connecting them, bails loosely mounted on the shafts for supporting the frame, rocking levers carried by the shafts and operable to open and close independently of the movement of the bails, and elevator-casing-engaging jaw members pivotally carried by the inner ends of the rocking levers.

3. A casing elevator comprising a frame consisting of side bars and transverse shafts connecting them, bails connected to the respective shafts for supporting the frame, inwardly projecting rocking levers on the shafts operable to open and close independently of the movement of the bails, and pivoted jaw members on the inner ends of the rocking levers, the bails having movement about the shafts independent of the rocking levers and the jaw members having movement independent of the rocking levers whereby the jaw members will be self-seating on the casing which the elevator is to support.

4. A casing elevator comprising a frame consisting of two side bars and two transverse shafts connecting them, two links, each comprising an inverted U-shaped member, through the ends of each of which one of the shafts projects, a pair of rocking levers loosely mounted on each shaft and extending toward the center of the frame, pivoted casing-engaging jaws, and trunnions on the respective jaws supported by the inner ends of the rocking levers.

5. A casing elevator comprising a frame consisting of two side bars and two transverse shafts connecting them, bails secured to the shafts, rocking levers on the shafts, 65 rocking jaw members carried by the inner ends of the rocking levers, and rods passing transversely through openings in the jaw members to hold them in vertical positions, the diameters of the openings being greater 70 than the cross sectional areas of the rods.

6. A casing elevator comprising a frame consisting of side bars and transverse shafts connecting them, bails secured to the frame, inwardly projecting rocking levers on the 75 shafts, vertical jaw members having swinging engagement with the inner ends of the rocking levers, and jaw spreading means carried by the frame, the jaw spreading means comprising toggle links connected to 80 the jaws and a swinging lever for operating the toggle links.

7. A casing elevator comprising a frame consisting of side bars and transverse shafts connecting them, bails secured to the frame, 85 inwardly projecting rocking levers on the shafts, vertical jaw members having swinging engagement with the inner ends of the rocking levers, jaw spreading means carried by the frame, the jaw spreading means comprising toggle links connected to the jaws 90 and a swinging lever for operating the toggle links, and a detent carried by the swinging lever for engagement with the notch in the frame to hold the toggle links 95 in extended position to maintain the jaws apart.

In testimony whereof I affix my signature.

GEORGE KRELL.
